UNITED STATES PATENT OFFICE.

EDGAR F. HATHAWAY, OF HORNELLSVILLE, NEW YORK.

DESIGN FOR A FENCE-STRAND.

SPECIFICATION forming part of Design No. 20,513, dated February 10, 1891.

Application filed December 26, 1890. Serial No. 375,892. Term of patent 14 years.

To all whom it may concern:

Be it known that I, EDGAR F. HATHAWAY, a citizen of the United States, residing at Hornellsville, in the county of Steuben and State 5 of New York, have invented and produced a new and original Design for Fence-Strands, of which the following is a specification.

The object of this design is to provide a novel, ornamental, and characteristic fencing-strand; and its leading features consist in an upper and lower longitudinal line, which lines are continuously undulated throughout their 10 length, and oblique cruciform lines, which cross each other centrally between the longitudinal undulated lines and extend in transverse lines across the latter substantially at right angles to a horizontal plane, said transverse lines being in pairs, wherein those of each 15 pair are in alignment, or approximately so, across the upper and lower undulated lines.

In the accompanying drawing, the figure is an elevation of a portion of the new and original fencing-strand.

In the drawing, the numerals 1 and 2 indicate, respectively, the upper and lower longitudinal lines, which are continuously and uni-

formly undulated throughout their length, and 3 and 4 indicate the oblique cruciform lines, which cross each other, as at 5, centrally between the lines 1 and 2. The cruciform 30 lines 3 and 4 extend in upper and lower transverse lines 6 and 7 across the undulated lines substantially at right angles to a horizontal plane. The transverse lines 6 and 7 are rectilinear and are arranged in pairs with those 35 of each pair in vertical alignment, or approximately so, across the upper and lower undulated lines.

The peculiar arrangement described and shown imparts a novel, ornamental, and characteristic appearance to the fencing-strand. 40

What I claim is—

The design for a fencing-strand, substantially as shown and described.

In testimony whereof I have hereunto set my 45 hand and affixed my seal in presence of two subscribing witnesses.

EDGAR F. HATHAWAY. [L. S.]
